UNITED STATES PATENT OFFICE.

FREDERICK M. VENZIE, OF PHILADELPHIA, PENNSYLVANIA.

BUILDING CONSTRUCTION.

Application filed February 27, 1925. Serial No. 12,016.

This invention, stated in general terms, relates to building construction, particularly floors and ceiling structures of concrete. In work of this character great difficulty is experienced with the labor problem. Not only must skilled labor be employed but the expense incident thereto is almost prohibitive. According to the present invention I propose to employ structural parts which may 10 be readily assembled by unskilled labor thus first eliminating the need for skilled labor and second, bringing building costs nearer normal, the advantages of which are readily apparent.

15 The invention consists of the novel construction hereinafter described and finally claimed.

The nature, characteristic features and scope of the invention will be more fully 20 understood from the following description taken in connection with the accompanying drawings forming part hereof, and in which:

Fig. 1 is a view in section of a floor and ceiling structure embodying the invention.

25 Fig. 2 is a top or plan view thereof.

Fig. 3 is a view in section taken at right angles to Fig. 1.

Fig. 4 is a view upon an enlarged scale of certain of the parts shown in Fig. 1.

30 Fig. 5 is a fragmentary view in plan, partly sectioned, of certain of the parts shown in Fig. 4; and

Fig. 6 is a detail view of one of the clips shown in Figs. 1, 3 and 4.

35 For the purpose of illustrating my invention I have shown in the accompanying drawings one form thereof which is at present preferred by me, since the same has been found in practice to give satisfactory and reliable results, although it is to be understood that the various instrumentalities of 40 which my invention consists can be variously arranged and organized and that my invention is not limited to the precise arrangement 45 and organization of the instrumentalities as herein shown and described.

Referring to the drawings in detail the numeral 10 designates I-beams, properly spaced apart for supporting floor plaster blocks 11 and ceiling plaster blocks 12. These blocks all have bevelled edges 13 so that between adjacent edges of the blocks, properly positioned, there occurs V-shaped openings, see Fig. 4. Each block has formed 55 therein at the time of molding a plurality of rods, some of which, those designated 14,

parallel the I-beams, and others of which, those designated 15, are arranged at right angles to the I-beams. All the rods are projected from the bevelled edges of the blocks, hook-fashion as at 16, see Fig. 4, the extreme ends of each rod being bent over the main part of the rods within the blocks, as at 17. The adjacent portions of the hook-like parts of the rods are secured together 60 by wire 18. Each I-beam has fitted thereover an elongated U-shaped clip 19, the opposed vertical edges of which are serrated or notched at 20, see Fig. 6. The bottoms of the clips are forked at 21 and apertured 65 at 22 and are bent around the rods 14, see Fig. 4, and nails 23 are driven through the apertures 22 into the ceiling blocks 12. This provides an efficient support for the ceiling blocks. The clips are provided with spurs 70 24 which are bent inwardly beneath the upper parts of the I-beams, see Fig. 4. Concrete or other plastic material is placed 75 within the V-shaped spaces between adjacent blocks as seen in Figs. 1, 3, and 4, the concrete having been omitted in Fig. 2, for clearer illustration. As best seen in Fig. 3, the forked ends of the clips 19 straddle abutting hook-shaped ends of the rods 14, and a prong 25 of the serrated portions of 80 the clips is bent over each spur 24 to prevent shifting thereof.

It will now be apparent that I have devised a novel and useful construction which embodies the features of advantage enumerated as desirable in the statement of the invention and the above description and while I have in the present instance shown and described the preferred embodiment thereof which has been found in practice to 90 give satisfactory and reliable results, it is to be understood that the same is susceptible of modification in various particulars without departing from the spirit or scope of the invention or sacrificing any of its advantages.

What I claim is:

1. In a structure of the character stated, spaced I-beams, floor blocks and ceiling blocks of plaster composition having bevelled edges there being a floor and ceiling block spanning adjacent beams, said blocks having embedded therein a plurality of rods which are projected from said bevelled parts hook-fashion, hook portions of adjacent 105 blocks being wired together, and means depending from the upper parts of said I-

beams for engaging certain of the hook-shaped ends of said ceiling blocks to support the same.

2. In a structure of the character stated, spaced I-beams, floor blocks and ceiling blocks of plaster composition having bevelled edges there being a floor and ceiling block spanning adjacent beams, said blocks having embedded therein a plurality of rods some of which parallel the I-beams and others of which are arranged at right angles thereto, which are projected from said bevelled parts hook-fashion, hook portions of adjacent blocks being wired together, and means depending from the upper parts of said I-beams for engaging certain of the hook-shaped ends of said ceiling blocks to support the same.

3. In a structure of the character stated, spaced I-beams, floor blocks and ceiling blocks of plaster composition having bevelled edges there being a floor and ceiling block spanning adjacent beams, said blocks having embedded therein a plurality of rods which are projected from said bevelled parts hook-fashion, hook portions of adjacent blocks being wired together, and means including clips having lower forked and hooked ends depending from the upper parts of said I-beams for engaging certain of the hook-shaped ends of said ceiling blocks to support the same.

4. In a structure of the character stated,

spaced I-beams, floor blocks and ceiling blocks of plaster composition having bevelled edges there being a floor and ceiling block spanning adjacent beams said blocks having embedded therein a plurality of rods which are projected from said bevelled parts hook-fashion, hook portions of adjacent blocks being wired together, means depending from the upper parts of said I-beams for engaging certain of the hook-shaped ends of said ceiling blocks to support the same, and nails for securing the lower extremities of said means to said ceiling blocks.

5. In a structure of the character stated spaced I-beams, floor blocks and ceiling blocks of plaster composition having bevelled edges there being a floor and ceiling block spanning adjacent beams, said blocks having embedded therein a plurality of rods which are projected from said bevelled parts hook-fashion, hook portions of adjacent blocks being wired together, and means depending from the upper parts of said I-beams for engaging certain of the hook-shaped ends of said ceiling blocks to support the same, adjacent faces of all of said blocks forming V-shaped portions which portions have a concrete fill.

In testimony whereof, I have hereunto signed my name.

FREDERICK M. VENZIE.
